Primary Examiner—Wallace R. Burke*Assistant Examiner*—M. Brown*Attorney, Agent, or Firm*—Rhodes & Ascolillo**[57] CLAIM**

The ornamental design for a portable botanical liquid dispenser, as shown and described.

DESCRIPTION

FIG. 1 is a perspective view of a portable botanical liquid dispenser showing my new design therefor; the broken line drawing representing a tree is for illustrative purposes only and forms no part of my design;

FIG. 2 is a top plan view;

FIG. 3 is a front elevational view, the rear elevational view being a mirror-image thereof;

FIG. 4 is a right side elevational view, the left side elevational view being a mirror image thereof; and,

FIG. 5 is a bottom plan view.

FIG. 1

FIG. 4

FIG. 5

FIG. 2

FIG. 3
